UNITED STATES PATENT OFFICE.

HENRY V. SMITH, OF BRIDGEPORT, CONNECTICUT, ASSIGNOR OF ONE-HALF TO EUGENE H. SMITH, OF BRIDGEPORT, CONNECTICUT.

PLATING-RACK.

No. 890,882.

Specification of Letters Patent. Patented June 16, 1908.

Application filed October 28, 1907. Serial No. 399,546.

To all whom it may concern:

Be it known that I, HENRY V. SMITH, a citizen of the United States, residing at Bridgeport, county of Fairfield, State of Connecticut, have invented a new and useful Plating-Rack, of which the following is a specification.

This invention relates to the electroplating of spoons, forks, &c. and has for its object to provide a rack for holding spoons and forks while in the electrolytic bath, which shall be so shaped as to "shadow" or protect the inner sides of the bowls and handles of spoons or forks, so that very much less silver will be deposited on the protected sides than on the exposed or outer sides, that is the sides toward the anodes in the bath, and which may be made of insulating material so that none of the precious metal, ordinarily silver, will be deposited thereon. It is of course well understood that in use the greater portion of the wear upon plated spoons and forks is upon the backs of the bowls and handles. It is desirable, therefore, to deposit double, more or less, the amount of silver upon the backs of spoons and forks that is deposited upon the inner sides thereof, and to perform this operation of practically double-plating the backs and single-plating the inner sides at a single operation, and furthermore to suspend the spoons and forks in such a manner that no marks will be left upon them.

With these and other objects in view I have devised the novel plating rack, of which the following description in connection with the accompanying drawing is a specification, reference characters being used to indicate the several parts.

Figure 1 is an elevation of my novel rack as in use; Fig. 2 a section of one of the forms detached, on the line 2—2 in Fig. 1 looking in the direction of the arrows, the position of a spoon in use being indicated by dotted lines; and Figs. 3 and 4 are elevations from different points of view, illustrating a variant form of the invention.

My novel rack comprises a frame 10 which is made of wire and a plurality of forms indicated by 11.

The frame may be made of any convenient design and may carry any required number of forms, for example, five as shown in the drawing, although a greater number of forms

is ordinarily placed upon each frame in use. The upper portion of the frame comprises a handle, indicated by 12, the side pieces of which are preferably provided with hook-shaped bends, indicated by 13, as a convenient means for suspending the rack in the bath. The forms may be made of any suitable material, which may be insulating material or not, as preferred, and are provided with convex faces, indicated by 25, to correspond substantially with the inner sides of the articles to be plated, as will be readily understood from Fig. 2, which illustrates a form especially adapted for use in plating spoons.

14 denotes retaining wires which are secured in the forms and simply serve as means for retaining the spoons or forks in position. These retaining wires are not electrically connected.

15 denotes supporting wires upon which the spoons or forks are suspended and which are electrically connected.

As a convenient means of constructing the forms I have shown in Fig. 2 a form made in a single piece and provided with a metal block 16 centrally recessed therein through which the supporting wires pass, the ends of the opening for the block being closed by plugs 24. A wire 17 extends outward from each block and is connected to a current wire 18. Wires 17 and also the lower cross piece of the frame, indicated specifically by 19, are preferably covered with insulating material 20, so that none of the precious metal will be deposited thereon. I thus effect a great saving in the cost of plating, as there is no loss of the precious metal by deposit on the rack, and accelerate the deposition of the precious metal on the spoons or forks to be plated.

The form illustrated in Figs. 3 and 4 differs from the other form in that instead of being made in one piece it comprises side pieces, indicated by 21, and cross pieces indicated by 22, the supporting wires being connected to wires 17 by means of wires 23.

The operation of my novel rack in use will be readily understood from Fig. 2, in which I have indicated the position of a spoon relatively to the form by dotted lines. The spoons or forks, as may be, are placed upon the forms, as shown,—two on each form, and

then the rack is suspended in the electrolytic bath by hook-shaped bends 13 or in any suitable manner.

Having thus described my invention I 5 claim:

1. A plating rack comprising a plurality of forms shaped to correspond with the inner faces of the articles to be plated and provided with supporting wires, a frame by 10 which the forms are carried and electrical connections with the supporting wires.
2. A plating rack comprising a plurality of forms made of insulating material and provided with supporting wires, said forms being 15 shaped to correspond with the inner faces of the articles to be plated, a frame by which the forms are carried, insulating material on the frame and electrical connections with the supporting wires.
3. A plating rack comprising forms having 20 supporting wires for the articles to be plated, a frame by which the forms are carried and insulating material on the frame to prevent deposition of metal thereon.
4. A form for electroplaters' use made of 25 insulating material and shaped to correspond with the articles to be plated, supporting wires in said form and electrical connections with the supporting wires.
5. A form for electroplaters' use having a 30

convex face to correspond with the bowl of a spoon and a shank to correspond with the handle of a spoon, supporting wires by which the spoon is carried and electrical connections with the supporting wires.

35

6. A form for electroplaters' use made of insulating material and having convex faces to correspond with the bowls of the spoons and shanks corresponding with the handles of the spoons and having a metallic block 4 recessed therein, supporting wires for spoons connected with the block and an electrical connection with said block.

45

7. A plating rack comprising a plurality of forms having opposite convex faces to correspond with the bowls of spoons, a frame by which the forms are carried and electrical connections, substantially as described, for the purpose specified.

8. A plating rack comprising a plurality of 50 forms made of insulating material, means for attaching spoons thereto and electrical connections.

In testimony whereof I affix my signature, in presence of two witnesses.

HENRY V. SMITH.
